UNITED STATES PATENT OFFICE.

FANNIE M. ULLMANN, OF YOAKUM, TEXAS.

BAG-SKID.

1,187,204.

Specification of Letters Patent. Patented June 13, 1916.

Application filed January 13, 1916. Serial No. 71,966.

To all whom it may concern:

Be it known that I, FANNIE M. ULLMANN, a citizen of the United States, residing at Yoakum, in the county of Lavaca and State 5 of Texas, have invented new and useful Improvements in Bag-Skids, of which the following is a specification.

My present invention pertains to the protection of cotton pick-sacks against wear 10 during the dragging of the same over the ground; and it contemplates the provision of a skid for the purpose, the said skid being adapted to rest under a sack and serve as a shoe incidental to the dragging of the 15 sack, and being detachably-connected to the sack so that the sack can be expeditiously removed from the skid for dumping or weighing or to give place to an empty sack.

Other objects and advantageous character- 20 isties of the invention will be fully understood from the following description and claims when the same are read in connection with the drawings, accompanying and forming part of this specification, in which:

25 Figure 1 is an inverted plan view of the skid constituting the best practical embodiment of my invention that I have as yet devised. Fig. 2 is an edge elevation of the skid showing the same in working position. 30 Fig. 3 is a fragmentary view, partly in section, showing the manner of detachably-connecting the skid body to one of the plates that are permanently attached to the sack. Fig. 4 is a plan view, partly in section, showing 35 one of the bolts for effecting the detachable connections. Fig. 5 is a perspective illustrating the arrangement of the pick-sack on the skid.

Similar numerals of reference designate 40 corresponding parts in all of the views of the drawings.

My invention contemplates the provision on each sack of metallic plates 1; the said plates being riveted or otherwise perma- 45 nently attached to a sack 2 in the position shown in Fig. 5 or in any other position compatible with the purpose of my invention, and being provided with protruding knuckles 3.

50 The body of my novel skid, which is num-

bered 4, is preferably, though not necessarily, formed of galvanized-iron, and is provided at its forward end and on its underside with an intermediate barrel-section 5 and end barrel-sections 6; the said sections 55 6 being spaced from the section 5 so as to afford intervening spaces for the reception of the knuckles of the plates 1 in the manner shown in Figs. 1, 3 and 5. As will be readily observed by reference to Figs. 2 and 5 the barrel sections 5 and 6 are inexpensively formed by bending the end portion of the skid body 4. The barrel section 5 is longitudinally-slotted as indicated by 7, and at the outer ends of said slots 7 angularly-disposed seats 8 are provided. Bolts 9 are movable in the barrel section 5 and into and out of the knuckles 3 and the barrel sections 6. The said bolts are moved through the medium of handle sections 10, said sections 70 10 being movable in the slots 7, and when the handle sections 10 are swung into the seats 8 it will be noted that the bolts will be held against casual retraction, with the result that in practice, there is no liability of a 75 pick-sack becoming accidentally disconnected from the skid. In this connection, it will be observed, that incidental to the dragging of the skid over the ground, the handle sections 10 extend rearwardly from the bolts 80 and are drawn after the bolts so that there is no liability of the dragging having a tendency to displace the handle sections 10 from the seats 8. When, however, it is desired, to disconnect the sack from the skid, it is 85 simply necessary to swing the handle sections 10 into alinement with the slots 7, and then retract the bolts 9 until the latter are clear of the knuckles 3 of the plates 1.

Having described my invention, what I 90 claim and desire to secure by Letters-Patent, is:

1. A skid designed for use in connection with a bag equipped with knuckles; said skid comprising a body formed of sheet-metal 95 and having its end portion bent to form at its underside an intermediate barrel and end barrels spaced from the intermediate barrel, and also having longitudinal slots in the intermediate barrel and angularly-disposed, 100

2
rearwardly-directed seats extending from said slots, bolts movable in the intermediate barrel and into and out of the end barrels, and handles movable in the longitudinal slots and into and out of the seats.

2. A skid designed for use in connection with a bag equipped with knuckles; said skid comprising a body having barrels constructed and arranged to be alined with the knuc-

cles, and bolts carried by the body and movable into and out of the knuckles.

In testimony whereof I have hereunto set my hand in presence of two subscribing witnesses.

FANNIE M. ULLMANN.
